UNITED STATES PATENT OFFICE.

SIXTE ARMAND COUPAL, OF GRANTS PASS, OREGON.

TENT.

Application filed June 25, 1925. Serial No. 39,574.

This invention relates to improvements in tents, and has for its special object the provision of a tent which, while light in weight and capable of being easily and conveniently set up for use and taken down and packed in close compass for storage or transportation, is of such geometrical form and construction and so trussed, without the use of obstructing center poles, as to be capable of resisting high wind pressures and to be proof against collapse or of being blown over in any ordinary wind storm.

A further object of the invention is to provide a tent which is adapted, by reason of its novel and improved and special structural features and characteristics, for all uses and in all climates and on all kinds of surfaces, for camping out purposes, where the use of a tent of great lightness of weight, maximum degree of portability, and proof against the action of the elements under all normal conditions, is desirable.

With these and other objects in view, which will appear in the course of the subjoined description, the invention consists of the features of construction, combination and arrangement of parts, hereinafter fully described and claimed, reference being had to the accompanying drawings, in which:—

Figure 1 is a view in elevation of the set-up tent, showing its geometrical form.

Figure 2 is a section thereof on line 2—2 of Figure 1.

Figure 3 is a perspective view of the set-up tent, viewed from the front and one side, and showing the same partially broken away to expose the interior truss framing.

Figure 4 is a top plan view of a portion of the sectional tetrapod truss frame.

Figure 5 is a sectional elevation thereof.

Figures 6 and 7 are perspective views of the upper extension sections of two of the staffs of the tetrapod truss frame, showing features of construction thereof.

Figure 8 is a longitudinal section through one of the staffs in extended condition.

Figure 9 is a detail section on line 9—9 of Figure 8.

Figure 9^a is a fragmentary perspective view in elevation showing one of the three tubular metal staffs and a brace bar connected therewith.

Figure 10 is a sectional perspective view looking down upon a staff and illustrating the connection therewith of coacting brace bars.

Figure 11 is a side elevation of a two-section tubular metallic staff of slightly modified form which may be employed.

Figure 12 is a similar view of another slightly modified sectional tubular metallic staff which may be employed.

Figure 13 is a side elevation of a sectional wooden staff.

Figure 14 is a cross-section on line 14—14 of Figure 13.

Figure 15 is a sectional elevation of another form of wooden staff.

Figure 16 is a cross-section on line 16—16 of Figure 15.

Figure 17 is a view similar to Figure 3 showing a modification in the means for connecting the staffs or legs of the frame sections.

Figure 18 is a sectional plan view on line 18—18 of Figure 17.

Figure 19 is a vertical section taken through the coupler head on the plane indicated by line 19—19 of Figure 18.

Figure 20 is a detail section on line 20—20 of Figure 19.

Figure 21 is a side elevation of one of the leg sections and showing the coupler parts connected therewith.

In carrying my invention into practice, I provide a tent 1, made of canvas, ducking or other suitable material and having four sides or walls 2, each of triangular shape and producing a tent body of pyramidal form. This tent body is provided with a floor or bottom wall 3, which may be of heavy canvas, ducking or other heavy tent material, and which is joined to the lower edges of the walls 2. This flexible tent bottom closes the base of the tent body against the entrance of dirt, dust, snow, rain, etc., and also against the entrance of any disturbing gusts of air liable in stormy weather to disturb the equilibrium or stability of the tent structure. One of the walls 2 of the tent structure may be provided with any suitable type of door 4 to afford ingress and egress to the occupants thereof.

The tent body is held supported and its pyramidal conformation maintained by an internal framing having supporting and bracing characteristics. This framing is of tetrapod type and comprises four corner staffs or legs 5, each preferably of folding or extension type, said staffs being arranged at the corner angles of the walls along the fold lines thereof and extending from the

bottom to the top or apex of the tent body. Each leg may be of the folding or extension type and capable of being disconnected or unstacked from its companion legs and folded or closed up so that the frame structure, with the collapsed tent, may be disposed in very close compass for maximum convenience in storage or transportation. One form of leg which may be employed is shown in Figures 3 to 8, inclusive. This leg is made of steel or other strong and durable metal and comprises three telescopic sections 6, 7 and 8 adapted to slidably telescope one within the other, so that the sections 7 and 8, 15 telescoped one within the other, may be substantially received within the section 6. These sections 6, 7 and 8 progressively decrease in diameter to permit of such telescopic action, and the inner ends of the sections 7 and 8 20 are provided with outstanding stop flanges 9 engageable respectively with instruck stop flanges 10 on the sections 6 and 7 to limit the outward or extension movements of said sections 7 and 8. The flanges 9 further serve as 25 guide members in conjunction with inturned guide flanges or members 11 on the relatively upper ends of the sections 6 and 7 to respectively stably guide the sections 7 and 8 in their movements. A spring-pressed latch 30 pin 12 is provided on the base section 6 to underlie and engage with the flange 9 of the section 7 when the latter is extended to hold it from collapsing and in extended position, while a latch member 13 is provided upon 35 the top section 8 to lock said section 8 in extended position. This latch member 13 preferably comprises a V-shaped member of spring wire enclosed within the section 8 and having its limbs provided with out-turned 40 locking arms or projections 14 movable in guide openings 15 in opposite sides of the section 8, the construction being such that the arms 14 will be normally pressed outwardly by the spring action of the limbs to 45 projected position for engagement with the flange 11 of the section 7, whereby the section 8 will be locked from inward movement, as will be readily understood. When it is 50 desired to collapse the section 8, this may be accomplished by pressing inwardly upon the arms 14 to cause them to recede and pass the flange 11 to allow the section 8 to be telescoped within the section 7.

The four extension props or legs 5, constructed as above-described, are adapted to be coupled at their upper ends and properly braced to hold them in stack formation. For this purpose, three of the four props are provided at their upper ends with coupling 55 arms 16 having angularly bent apertured end portions or eyes 17, while the fourth prop is provided with an arm 18 having an angularly disposed coupling or locking pin 19. The eyes 17 of the three props provided 60 therewith are adapted to be disposed in lap-

ping relation or overlie one another at the apex of the tent body and to be engaged and interlocked by the pin 19 of the fourth prop, whereby the upper ends of the prop are interlocked or detachably united against possibility of disconnection. If desired, a coupling ring 20 may be provided for use, with or without the connecting means above-described, for holding the upper ends of the props connected and affording additional security in the use of such ring with the locking connections. This ring is adapted to be slipped down upon the upper ends of the poles and to be engaged and interlocked with seat recesses 21 formed therein, whereby the ends of the poles will be held assembled and prevented from spreading apart. In addition, truss members or cross braces 22 may also be employed between the props below and adjacent to their upper ends. These truss members or cross braces may consist of rods or bars having hooked end portions 23 adapted to be fitted in receiving slots 24 formed in the props and interlocked with the bottom walls of said slots to detachably couple the legs together, allowing the bars to be slipped into and out of position and when applied to form a rectangular bracing structure below and in the region of the apex of the tent, whereby the internal bracing structure is rendered rigid against deflection under pressures on the tent walls, and whereby the pyramidal conformation of the tent body will always be maintained. The internal framing and bracing structure constructed as above-described, is obviously adapted to be easily and conveniently assembled in setting up the tent and disassembled in taking down the tent, and when disassembled the props or legs may be collapsed so that all of the elements of the framing and bracing structure may, with the collapsed tent body, be packed in compact form for storage or transportation. As such a structure when set up is, by reason of its geometric formation, of great strength, a framing and bracing structure which is light in weight and yet of great strength may be produced, so that the entire outfit may be of such light weight that it may be conveniently carried by campers or porters in the absence of transportation equipment. The lower ends of the tubular lower prop section 6 may be suitably angled or beveled off, as indicated at 25 to adapt them to assume the proper angle of inclination and rest squarely upon the floor 3.

In Figure 11 I have shown a modified form of pole or staff 5^a which may be employed under some conditions in place of the staff 5, the said staff 5^a consisting of but two telescopic sections 6^a and 8^a instead of three. This type of staff may be used when it is desired to reduce weight to the lowest possible degree. The general structure of the 120 125 130

staff in this case is the same as that of staff 5 with the exception noted and with the further exception of a slight modification in the form and construction of the coupling arm 5 and pin of the staff provided therewith. As shown, this coupling arm 18^a may be slightly curved and provided with an opening for the reception of a removable coupling pin 19^a.

10. In Figure 12 I have shown still another modified form of pole or staff 5^b, which may consist of three tubular sections as in case of the staff 5 or two tubular sections as in case of the staff 5^a. In the present instance 15 the staff 5^b is shown as comprising three tubular sections 6^b, 7^b and 8^b reversed in their order of arrangement with respect to the structure of the staff 5, that is to say, the top staff section 6^b being the largest in 20 diameter, the intermediate staff section 7^b of mean diameter and the lower staff section 8^b of smallest diameter. In this case, the strongest staff section is at the top and gives increased bracing strength at this point, so 25 that if desired, the interlocking connections at the upper ends of the staffs may be dispensed with and said staffs provided with angular or inclined abutment surfaces 26 to rest against one another, so that by the use 30 of the coupling ring 20 engaging the notches 21 the staff members may be held joined in a firm and rigid manner and without additional fastenings.

35 In Figures 13 and 14 I have shown still another modified form of staff construction which may be employed, the staff 5^c therein shown consisting of two half round wooden sections 6^c and 8^c, the section 6^c carrying a sliding sleeve 27 embracing the section 8^c and the latter being provided with a pivoted locking ring 28 embracing the section 6^c and adapted for interlocking engagement between any two of a series of headed pins or locking projections 29 thereon for adjustably locking the sections together to provide a pole or staff of a desired length within given limits. The ring 28 is so mounted that when disposed at right angles to the staff sections it will engage between the heads of adjacent studs 29 for interlocking engagement therewith, but by slightly tilting one staff section with respect to the other and adjusting said ring to an angular position the slidble motion of one staff section with respect to the other will be permitted for adjusting and collapsing operations, as indicated in dotted lines in Figure 13. The staff section 6^c in this case is provided with a coupling bracket 16^a having an apertured eye 17^a, which type of bracket may be provided on three of the posts or legs for coaction with a suitable type of coupling pin bracket on the fourth prop or leg.

40 In Figures 15 and 16 I have shown another slightly modified form of prop or staff,

conforming somewhat in structure to that shown in Figures 13 and 14, and wherein the prop is made of two sections 6^d and 8^d of wood, each prop section being of triangular form in cross-section. These two sections are hingedly united at their adjacent ends, as at 30, adapting the same to be disposed end for end in longitudinal alinement, for service use, or swung on their hinge connection to a position in parallel relation 45 to each other for folding into close compass for storage or transportation. A sliding sleeve 31 is provided on the prop, which is adapted to be arranged to embrace the hinged ends of the prop sections to hold the same in alinement and against pivotal movement when adapted for service operation, which sleeve may be slid upward on the section 6^d, as shown in dotted lines, to expose the hinge joint and permit said prop sections to be folded or collapsed. A locking pin 32 is provided on the section 8^d to hold the sleeve 31 from slipping downward beyond a predetermined position when disposed to hold the hinged ends of the prop sections 50 rigid. By making the props of triangular form in cross-section a set of legs or props of this type, when folded, may be grouped and tied very closely together, as shown in Figure 16, so as to occupy very 55 small space when the outfit is collapsed for storage or shipment.

59 In Figures 17 to 21, inclusive, I have shown a modification in the means for connecting the legs of the framing. As shown 60 therein, I provide a coupler head consisting of a pair of inverted U-shaped members 33, preferably made of spring strap metal and arranged at right angles to each other. The return bend portions of these members are 65 arranged in crossed relation and connected by fastening means, such as a bolt 34. The legs 35 of these members depend and are arranged so as to extend into the upper ends of the leg sections 8^e. A coupler ring 36, 70 similar to the ring 20, is provided to seat within notches 37 in the ends of the legs 8^e and to be held therein by the coupler legs 35, which extend downwardly across the 75 notches 37 and hold the ring from displacement therefrom. Each leg 35 is provided with a locking pin 38 to engage a locking opening 39 in the leg section 8^e, whereby the coupler leg 35 and leg section 8^e of the framing are held interlocked and from displacement. The locking pins 38 are held engaged with the openings 39 by the bowing or spring action of the legs 35, which have sufficient resiliency to permit them to be 80 pressed back for a releasing action so that the parts can be readily disconnected when desired. This construction provides a type of coupler or fastening connection which will hold the leg sections of the tetrapod frame securely assembled, while admitting 85

of their easy and quick disassembly. The bolt 34 may form a pivotal connection between the coupler members 33 whereby, when the coupler is disconnected, the parts thereof may be folded upon one another to lie nested, for greater convenience in storage and packing.

The tent may be set up for use by placing the tetrapod frame elements on the inside 10 of the tent body and erecting frame with connecting braces in an obvious manner, which operation may be performed within a very short period of time. By reversing this operation the frame structure may be 15 disassembled and the parts thereof collapsed and packed with the collapsed tent in very close compass for storage or transportation. It will thus be seen that the tent structure affords great convenience in setting up and 20 taking down operations, as well as in transporting the same on marches or from place to place for use, and in storing the same away when its use is not required.

A great advantage of my tent structure is 25 that, owing to its geometric formation, and its type of internal bracing, it entirely dispenses with the use of interfering center poles, or of weighty poles for holding the tent in position against weight collapse or 30 wind pressures, as well as the use of outside stakes and guys or other external bracing and anchoring means, all of the tent supports being wholly enclosed and in such close 35 relationship to the walls of the tent as to leave the entire interior space of the tent free for occupancy. Owing to the fact that 40 the tent body from bottom to top is of pyramidal form, it offers on all sides a surface resistance that is predominantly greater at its base and at the same time so inclined 45 that the impact of the wind on any of its walls produces a greater lateral and downward pressure than it does in the horizontal direction, the pressure of the wind, in other words, serving to increase the anchorage 50 hold of the tent at its base, instead of tending to destroy the equilibrium of the tent or to push it away from its anchorage. The 55 natural result of this is that such a tent will maintain its erect position, and will not be blown over or displaced from its established position under any normal circumstances or under wind pressures even to the extent of gales, so long as its original geometric shape 60 is preserved. The tent being made of flexible material, reliance is placed, for the preservation of its geometric shape, upon the internal bracing, and this internal bracing, as 65 constructed, is designed to give the highest possible internal resistance to any change in the formation of the tent walls or of the tent body itself under wind pressures falling upon any of the surfaces thereof. Assuming 70 that the wind pressure strikes one of the side walls of the tent, any one of them, the

legs of the tetrapod frame on that side of the tent will receive and sustain the impact of the wind pressure and serve to maintain the stability of such wall, while the legs or props of the tetrapod frame on the opposite 75 side of the tent will serve as braces against both the lateral as well as the horizontal components of the wind pressure. In the case of the props which, in the example noted, act as propping or truss bracing elements, it will be observed that they lie at such a propping angle that they prop at a high elevation against a force at the impact side, where the impact is mainly at a lower point, so that there will be opposed to the displacing force of the wind the angular resistance of the apex of the structure, together with the rectangular and surface resistance of the floor, combined with the resistance of the cross braces of the frame 80 structure, all acting and contributing to establish a resistance against collapse or displacement of the tent greater than the wind forces exerted thereagainst under all normal 85 conditions, up to the pressures of high gales, so that the equilibrium of the tent and its established position will not be disturbed. Actual tests show that a tent and reinforcing framing of the construction herein disclosed will maintain the conformation of 90 the tent under very high wind pressures with the use of very light structural elements in the formation of the frame structure. By the provision of the tent floor, of 95 flexible type and joined to the tent walls, it will be apparent that rain, snow, dust and dirt will be excluded, as well as air pressures tending to disturb the stability of the tent, and that in case of a wind the air pressure upon the tent walls, tending to force the tent 100 downwardly, will cause the tent bottom to exert a frictional resistance against the ground or other surface on which it rests which is multiplied in direct ratio with the 105 strength of impact of the wind, whereby the resistance of the tent to displacement from its side practically ensures firm anchorage 110 of the tent under all conditions of service. The tent will therefore maintain its position on all surfaces, except possibly on a slippery 115 surface, such as ice, under very heavy wind pressures, but when used on ice may be held by auxiliary means against sliding displacement with the use of less anchorage equipment than is required under ordinary conditions in tent construction.

Having thus fully described my invention, I claim:

1. A tent having four walls each of triangular shape and providing a tent body of pyramidal form, a tetrapod frame formed of corner props extending from bottom to top of the tent body at the corner angles of its walls, said props having interlocking connections at their upper ends, a coupling and 120

bracing member embracing said props below and adjacent to their coupled ends, and connecting braces between the props and across the tent walls below said coupling and 5 bracing member and between the same and the horizontal center of the tent.

2. A tent comprising a flexible tent body of pyramidal form and having a flexible bottom continuous with its walls, a tetrapod 10 frame formed of corner props extending from bottom to top of the tent body at the corner angles of its walls, said props having interengaging interlocking connections at their upper ends, a coupling and bracing 15 member embracing the props below and adjacent to their coupled upper ends, and bracing connections between the props and across said walls, arranged below said coupling and bracing member and at a point 20 between the same and the horizontal center of the tent.

3. A tent comprising a tent body of pyramidal form, a tetrapod frame formed of corner props extending from bottom to top of 25 the tent body, said props having their upper ends converging and provided with readily releasable interlocking connections, and said props being provided adjacent to and below their interlocking upper ends with 30 grooves, a coupling and embracing band engaging said grooves in the props, and brac-

ing connections between the props and across the tent walls, said bracing connections being disposed beneath said coupling and embracing band and between the same 35 and the horizontal center of the tent body.

4. A tent comprising a flexible tent body of pyramidal form, a tetrapod frame formed of corner props extending from bottom to top of the tent body, said props having their 40 upper ends converging and provided with readily releasable interlocking means, and each prop comprising at least a hollow section provided with a slot, a coupling and bracing band embracing the props adjacent 45 to and below their interlocking ends, and bracing connections extending between the props at a point between said band and the horizontal center of the tent, said connections having hooked ends engaging the slots 50 in the props.

5. A tent comprising a pyramidal tent body, supporting props at the corners of the body and extending to the apex of the body, interlocking means detachably connecting 55 the upper converging ends of said props, the props being provided with grooves or recesses, and a locking and bracing band extending around the props and engaging the grooves or recesses therein. 60

In testimony whereof I affix my signature.
SIXTE ARMAND COUPAL.
